(57) **CLAIM**

We claim the ornamental design for a photo alarm clock, as shown and described.

DESCRIPTION

FIG. 1 is a front perspective view of a photo alarm clock.

FIG. 2 is a rear perspective view of the photo alarm clock illustrated in FIG. 1.

FIG. 3 is a front elevational view of the photo alarm clock illustrated in FIG. 1.

FIG. 4 is a rear elevational view of the photo alarm clock illustrated in FIG. 1.

FIG. 5 is a right side view of the photo alarm clock.

FIG. 6 is a left side view of the photo alarm clock.

FIG. 7 is a top plan view of the photo alarm clock.

FIG. 8 is a bottom plan view of the photo alarm clock.

FIG. 9 is a front elevational view of the photo alarm clock illustrated in FIG. 1 in a closed position.

FIG. 10 is a rear elevational view of the photo alarm clock illustrated in FIG. 1 in a closed position.

FIG. 11 is a top plan view of the photo alarm clock shown in a closed position; and,

FIG. 12 is a bottom plan view of the photo alarm clock shown in a closed position.

The portions of the photo alarm clock in broken lines are shown for illustrative purposes only and form no part of the claimed design.
